[57] CLAIM

The ornamental design for a reconfigurable microscope toy, as shown and described.

DESCRIPTION

FIG. 1 is a front elevational view of a reconfigurable microscope toy showing my new design;

FIG. 2 is a rear elevational view thereof;

FIG. 3 is a top plan view thereof;

FIG. 4 is a bottom plan view thereof;

FIG. 5 is a right side elevational view thereof, the side opposite being a mirror image;

FIG. 6 is a front perspective view of the design shown in FIGS. 1 through 5 in a humanoid robot configuration;

FIG. 7 is a front elevational view thereof;

FIG. 8 is a rear elevational view thereof;

FIG. 9 is a top plan view thereof;

FIG. 10 is a bottom plan view thereof;

FIG. 11 is a right side elevational view thereof;

FIG. 12 is a left side elevational view thereof;

FIG. 13 is a front perspective view of the design shown in FIGS. 1 through 5 in a cannon configuration; and,

FIG. 14 is another front perspective view thereof with the barrel member in a raised position.
